SNAP-ACTION CAP

Milton Ostrowitz, Hillside, N.J., assignor to Gilbert Plastics, Inc., Hillside, N.J., a corporation of New Jersey

Filed Jan. 28, 1959, Ser. No. 789,673

3 Claims. (Cl. 220—60)

This invention relates to a closure for containers which have a circumferential bead and a discharge valve above the bead for release on thumb pressure to discharge the desired quantity of contents of the container, under gas pressure.

The invention provides a flexible, snap-action cap of novel structural features, making it highly practical and effective in application to the bead of the container, in covering relation to the discharge end of the container. The cap of the present invention incorporates novel registering and latching means as shown in the accompanying drawing and below described and claimed.

In the drawings, wherein similar reference characters indicate like parts:

Fig. 1 is a vertical, sectional view of a device embodying the invention, taken at line 1—1 of Fig. 2.

Fig. 2 is a bottom plan view thereof and,

Fig. 3 is a fragmentary vertical elevational view, showing the device applied to a container.

In the Fig. 1 form of this invention, cap 10 is shown to comprise a bottom portion 11 of given diameter, and a depending wall 12 extending therefrom and defining therewith a cup-shaped member, for application to a container, such as designated at 13 in Fig. 3, having a marginal bead 14' adjacent the discharge end 17 of the container. The free marginal edge 14 of cap 10 is formed of greater diameter than the bottom portion 11 thereof, and means are provided extending inwardly of the cap wall in spaced relation for engagement with the top and bottom edges (15 and 16, Fig. 3) of the marginal bead 14' of the container 13, to thereby position the cap over the bead 14' and to cover the adjacent discharge end 17 of the container. In the Fig. 1 form, said means include ribs 18 extending circumferentially inwardly (Fig. 2) of the free edge 14 of the wall of the cap, for engagement with the underside 16 of the bead (Fig. 3) when the cap is positioned thereover and means 19 extending inwardly of the container wall above the ribs 18 and in aligned spaced relation thereto, to engage the upper edge 15 of the bead when the cap is positioned thereover. The means 19

2

are shown in Fig. 1 as annular ribs or bars formed circumferentially inwardly of the wall of the cap above the free edge 14 thereof and in spaced relation thereto, to engage the upper edge 15 of the bead (Fig. 3) when 5 the cap is positioned thereover. Said inwardly extended bars 19 are preferably tapered toward the bottom 11 of the cap for reinforcement and to enhance their positive engagement thereof with the bead 14', on application of the cap to the container, as above described. The 10 cap 10 may be made of any suitable flexible material, and the parts so proportioned that when the cap is initially positioned on the container, only a slight amount of force is required to snap the free edge 14 and ribs 18 of the cap over the bead and into engagement with 15 the underside 16 thereof. The ends of the bars 19 adjacent the ribs 18 are formed essentially parallel to said ribs so as to have positive interengagement with the upper edge 15 of the bead 14', to latch the parts against accidental movement or displacement. The cap 20 may be readily grasped and snapped off the bead when it is desired to disengage the same from the container; the engagement and disengagement operations may be repeated without appreciable wear on the parts, little or no appreciable effort and dexterity being required for 25 the purpose.

Having thus described my invention, what I claim as new and desire to secure by Letters Patent is:

1. A snap action cap for registering latching engagement with the marginal bead of a container and for 30 covering the adjacent discharge end of the container, comprising a bottom portion of given diameter and a depending wall extending therefrom, said wall having a free marginal edge of greater diameter than the bottom portion, said wall thereby sloping outwardly from the 35 bottom portion, said cap being made of flexible material, a plurality of annular elongated ribs formed circumferentially inwardly of and parallel to the free edge of the wall of the cap at equidistant diametrically spaced points therealong for snapping interlocking engagement 40 with the underside of the container bead, a plurality of equidistantly spaced bars extending axially along the inner wall of the cap toward the ribs in alignment therewith and terminating a distance short of the ribs substantially equal to the thickness of the bead.
- 45 2. In a snap action cap as set forth in claim 1, said inwardly extended bars being tapered toward the bottom of the cap.

3. In a snap action cap as set forth in claim 1, the lower ends of said bars adjacent the ribs being substantially parallel to the ribs.
